[57] **CLAIM**

The ornamental design for a storage bin, as shown and described.

DESCRIPTION

FIG. 1 is a left side elevational view of a storage bin showing our new design, the opposite side being a mirror image thereof;

FIG. 2 is a top plan view thereof;

FIG. 3 is a bottom plan view;

FIG. 4 is a front elevational view thereof;

FIG. 5 is a rear elevational view thereof;

FIG. 6 is a left side elevational view of a modified form of the storage bin, the opposite side being a mirror image thereof;

FIG. 7 is a top plan view thereof;

FIG. 8 is a bottom plan view thereof;

FIG. 9 is a front elevational view thereof; and

FIG. 10 is a rear elevational view thereof.
